UNITED STATES PATENT OFFICE.

ROBERT R. WAY AND THOMAS F. MASON, OF WEBB CITY, MISSOURI.

BELTER.

1,273,701.

Specification of Letters Patent. Patented July 23, 1918.

Application filed May 15, 1917. Serial No. 168,836.

To all whom it may concern:

Be it known that we, ROBERT R. WAY and THOMAS F. MASON, citizens of the United States, and residents of Webb City, in the 5 county of Jasper and State of Missouri, have invented certain new and useful Improvements in Belters, of which the following is a specification.

This invention relates to belters and it is 10 the dominant object of the same to provide a belter which can be easily and quickly attached to the periphery or rim of a pulley or like element in a manner to secure a portion of a power transmitting belt thereto 15 whereby, when the pulley is rotated, the belt will be automatically arranged thereabout.

Another object of the invention is to provide a belter capable of adjustment, thus, 20 allowing the same to be used in connection with pulleys having different sizes or widths of rims.

Among other aims and objects of the invention may be recited, the provision of a 25 device of the character mentioned with a view to compactness, and in which the number of parts are few, the construction simple and the cost of production small.

Other objects will be in part obvious and 30 in part pointed out hereinafter.

The invention accordingly consists in the features of construction, combinations of elements, and arrangement of parts, which will be exemplified in the construction hereinafter set forth, and the scope of the application of which will be indicated in the following claims.

In the accompanying drawings, wherein is shown one of various possible embodiments of our invention;

Figure 1 is a side elevation partly in section of the improved belter as applied to a section of a pulley and power transmitting belt,

Fig. 2 is a transverse section through the belter, and

Fig. 3 is an end elevation thereof.

Similar characters refer to similar parts throughout the several views of the drawings.

Referring now more specifically to the drawings, the improved belter may be stated to comprise a plurality of telescopic clamping sections designated 1 and 2, each of the 55 said sections having formed upon their outer ends angularly disposed arms 3 and 4, the

arm 3 having the inner face thereof provided with a plurality of longitudinally disposed serrations 5. Upon the portion 4 of the section 1 a clamping jaw 6 is pivotally mounted between the bifurcated extremity thereof as at 7, and has formed upon its upper end a laterally extending finger 8, both the finger and the jaw being provided with serrations 9, the purpose of 65 which will be subsequently apparent.

Upon the telescoping portion of the clamping section 2 a rack 10 is formed while upon the outer end of the telescoping portion of the clamping section 1 a pawl 11 is pivotally 70 mounted in a slot or way 12 formed therein and is normally maintained in engagement with the teeth of the rack 10 by means of a coil spring 13 arranged beneath the free end thereof. By this means, it will be 75 appreciated, that adjustment of the clamping sections 1 and 2 is permitted and as a result, the belter can be used in connection with pulleys having rims of different size and widths. Further, the angular portions 80 3 and 4 of the said clamping sections may be much more securely engaged with the marginal edges of the pulley rim as shown in the Fig. 1, thereby preventing undue circumferential movement of the belter when 85 in use.

A loop or bail 14 is pivotally engaged with a portion of the angularly disposed arm 3 of the clamping section 2 and is adapted to be engaged by a cord, chain or 90 other flexible connection, which connection has its remaining extremity secured to a fixed object, whereby the belter may be safely used in connection with fly wheels arranged above delicate machinery and the 95 like without liability of damaging the same in the event of accidental displacement of the belter.

In operation, when it is desired to arrange the belt B about the rim of the pulley P, 100 the telescopic clamping sections 1 and 2 are properly adjusted to accord with the width of the rim and are arranged over a portion of the said belt and then moved into engagement with the opposite marginal edges 105 of the pulley rim, the serrations 5 formed upon the arm 3 positively engaging one marginal edge while the serrated clamping jaw 6 with its laterally projecting finger 8 securely engages the opposite side edge of 110 the pulley. By arranging the finger 8 between the belt B and the pulley P it will be

understood that movement of the pivotal clamping jaw 6 with relation to the pulley rim will be prevented, thereby insuring a positive connection between the same and the belt.

Manifestly, the construction shown is capable of considerable modification, and such modification as is within the scope of our claims, we consider within the spirit of our invention.

We claim:

1. A belter including a plurality of telescopic clamping sections having angularly disposed arms formed on their free ends, a pivotal jaw mounted on one of said arms, one of said sections having a rack formed on its telescopic portion, and a pawl arranged on the telescopic portion of the remaining section engageable with said rack.
2. A belter including a plurality of telescopic clamping sections, means for maintaining said sections in adjusted positions, a pivotal jaw having a laterally extending

finger formed thereon, one of said sections having a rack formed on its telescoping portion, and a pawl arranged on the telescopic portion of the remaining section engageable with said rack.

3. A belter including a plurality of telescopic clamping sections having angularly disposed arms formed on their free extremities, one of said arms having a serrated portion, a pivotal jaw mounted upon the free end of the remaining arm, a serrated laterally extending finger formed upon the upper portion of said jaw, one of the clamping sections having the telescoping portion thereof provided with a rack, and a spring pressed pawl mounted on the telescoping portion of the remaining clamping section engageable with the rack.

In testimony whereof we affix our signatures hereto.

ROBERT R. WAY.
THOMAS F. MASON.
